UNITED STATES PATENT OFFICE.

LYMAN R. BLAKE, OF BOSTON, MASSACHUSETTS.

IMPROVED CONSTRUCTION OF BOOTS.

Specification forming part of Letters Patent No. **85,989**, dated January 19, 1869.

To all whom it may concern:

Be it known that I, LYMAN R. BLAKE, of Boston, in the county of Suffolk and State of Massachusetts, have invented Improvements in the Construction of Boots and Shoes; and I do hereby declare that the following, taken in connection with the drawings which accompany and form part of this specification, is a description of my invention sufficient to enable those skilled in the art to practice it.

In the United States Patent No. 42,622, dated May 3, 1864, granted for the invention of Gordon McKay and myself, there is shown a gage on the upper surface of the horn of a sole-sewing machine surrounding the needle-hole in the end of the horn, said gage being designed for use with a pattern to be secured on that surface of a turned shoe-sole which comes outermost when the shoe is finished, though innermost when the vamp and sole are sewed together; and in the United States Patent No. 44,388, dated September 27, 1864, granted for my invention, there is shown a shoe not made as a "turn," in which the vamp and sole are united by stitches not passing through or into an inner sole, which inner sole serves, in construction, the temporary purpose of a medium, to which the vamp is fastened, and which may be torn out, or which, if left in place, serves only the further purpose of a filling.

Now, this invention consists, first, in the employment of a pattern under the inner surface of the sole of a boot or shoe not made as a "turn" for a guide against a projection on the end of a sewing-machine horn, and surrounding the needle-hole therein, and also for a medium to which to secure the vamp in lasting it, preparatory to sewing the sole and vamp together; and said invention further consists in such a pattern made with its upper portion of leather or other material suited to receive and hold lasting-tacks, and with its lower surface of iron or other material suited to stiffen the leather and to turn the points of the lasting-tacks.

The object of my invention is to facilitate the production of such boots and shoes as are described in my aforesaid Patent No. 44,388, they being designed to supersede turned shoes, to which they are much superior, as the material is not strained and damaged by any turn-

ing operation, and the lining is left smooth and of the proper size to take its share of the stress brought upon the boot or shoe in wearing.

In the drawings, Figure 1 represents, in cross-section, a shoe which has but a single sole, and is not made as a "turn," but right-side out, this view showing a portion of a sewing-machine horn, marked *a*, with the projection *b* thereon, which has been before referred to. The sole is denoted by *c*, and the vamp and lining thereof by *d*.

In preparing for lasting use is made of a compound pattern, which serves the double purpose of a guide against the projection *b* and of a medium to which to secure the vamp in lasting it, and to which also the sole *c* is temporarily attached. This pattern is made both shorter and narrower than the outer sole, to an extent which will admit half of the diameter of the projection *b* between the edge of the pattern all around its periphery and the central line of the seam to be formed around the sole. The pattern is made of two thicknesses or layers, secured together, one layer, marked *e*, being of leather or other material suited to receive and hold lasting-tacks, which are driven through the edges of the vamp, as seen at *f*, the other layer being of metal, and marked *g*, against which the points of the lasting-tacks turn or clinch.

The operation with this pattern is as follows: It is centrally located and slightly or temporarily fixed on the sole of a last, with the leather surface of the pattern uppermost, and the last is then placed in a vamp, the edges of which are drawn over the pattern, and lasting-tacks are driven through the edges of the vamp into the leather of the pattern, the points of the tacks turning, as shown in Fig. 1, against the metal plate *g*. The sole *c* is then centrally located over the pattern, to which it is temporarily secured, and when the last is drawn out from the shoe it is in readiness to be slipped upon the horn *a* of a sole-sewing machine for the purpose of having the vamp *d* and sole *c* united by a seam of stitches extending around the sole, the stitches being represented in the drawings by *h*, and may be left to appear on the surface of the sole, or may be hidden from view in a cut or channel in a manner well known.

After the sewing is completed the fastenings by which the outer sole is temporarily secured to the pattern are withdrawn, and the pattern is pulled out from within the shoe, bringing with it the lasting-tacks which tear out from the vamp. The tacks are then removed from the pattern, which is then again ready for use, as before explained.

Fig. 2 of the drawings shows a cross-section of a shoe as it will appear after the pattern has been removed.

I claim—

1. In the manufacture of boots and shoes, the described process, which consists in the employment of a pattern for the purposes of a guide and a lasting medium.

2. Also, the pattern made of hard and soft materials, substantially as and for the purposes specified.

LYMAN R. BLAKE.
